UNITED STATES PATENT OFFICE.

R. EDWARD BALL, OF NEW YORK, N. Y.

DYNAMO-ELECTRIC MACHINE.

SPECIFICATION forming part of Letters Patent No. 279,476, dated June 12, 1883.

Application filed May 9, 1883. (No model.)

To all whom it may concern:

Be it known that I, R. EDWARD BALL, a citizen of the United States, residing at New York, in the county of New York and State of New 5 York, have invented certain new and useful Improvements in Dynamo-Electric Machines, of which the following is a specification, reference being had therein to the accompanying drawings, wherein—

10 Figure 1 is a vertical longitudinal section of a dynamo-electric machine embodying my invention. Fig. 2 is an elevation of the armatures drawn to an enlarged scale, illustrating the position of the brushes. Fig. 3 is an elevation of armatures and rings therefor, showing the latter connected to the former at two or more points. Fig. 4 is a transverse section of same. Fig. 5 is a diagram of armature-rings and commutator, illustrating the mode 15 of arranging connection between said parts; and Figs. 6, 7, 8, and 9 show modifications of my invention.

20 My invention has relation to dynamo-electric machines, and has for its object to mechanically simplify the same, to reduce the amount of copper used in their construction, to obtain increased efficiency in working effect, and to augment their electrical capacity.

25 It is well known that the dynamo-electrical machine as a producer of electrical energy has a high efficiency, but its actual and practical efficiency in the production of light is low, and probably in the most efficient plants does not exceed sixty per cent. of the mechanical 30 energy expended in its production. While a dynamo may convert, say, ninety per cent. of the mechanical energy transmitted to it into electrical energy, not much more than two-thirds of that energy is utilized in the arc, the 35 remainder being given off as heat and dissipated in the machine itself, which in a great measure is due to the large ratio of the resistance of the machine to whole circuit. Then, again, the capacity of the dynamo is to a certain extent limited, and to obtain large currents it must be run at a very high rate of speed. If the diameter of the armature be increased, the size of the pole-pieces of the field-magnets must be enlarged. Consequently their 45 magnetic intensity for currents of equal magnitude is diminished, thereby requiring a pro-

portionately stronger field. If the amount of wire on the armature be increased or wrapped to a greater thickness around its core, the latter or induced body is thereby moved farther 55 away from the field of magnetic influence, which decreases the electrical effect and increases the resistance in the armature. To avoid such defects I employ two or more armatures of a particular construction, which 60 revolve in proximity to one another, so that the magnetic polarity of one forms the inducing agent for the other, and vice versa; or, in other words, the armatures have a mutual inductive action upon each other. The armatures may be 65 revolved in opposite directions, or in the same direction; but in all cases they are so arranged and rotated that their inducing and induced parts move in opposite directions when in proximity to one another. The armatures may 70 be placed one within the other, or face to face or side to side; or they may be otherwise located in any suitable or desirable manner. The provision of two or more armatures, constructed as hereinafter described, to electrically 75 act and react on each other to generate electrical energy permits of their extension to any desired size for the purpose of increasing their capacity to generate such energy. To 80 augment the working efficiency of such current or energy, it is necessary to decrease the resistance which said armatures offer to the passage of the currents through them. Hence I bring the induced iron cores of the moving armatures as close together as possible. To 85 do so I cover them with but one or two layers of copper wire. Therefore by such construction I not only effect a saving in the amount of copper used, thereby decreasing the resistance in the armature or internal circuit of the 90 dynamo, but also give the core of each armature the benefit of the electrical inductive force of the wire on the core of the other armature.

95 My invention has for its further object to provide an armature of very low resistance without materially decreasing its electrical capacity. To accomplish such result, the armature is divided into a number of parallel circuits with corresponding polarity-points by 100 connecting each commutator-block to said armature at two or more places. Referring

to the accompanying drawings, A, Fig. 1, represents the base-plate or frame of a dynamo, having standards A' A' with elongated bearings A² A², for separate shafts, B B', respectively, which are hollow and provided with driving-pulleys B³ B³, commutators C C', and armatures E E'. Each of the latter is securely mounted upon the end of its respective shaft, and they are shown as being one within the other, E being the external and E' the internal armature. Each armature is composed of an iron ring or annular core-piece, wound with endless coils of insulated wire in any desired or suitable manner; but I prefer to so wind said coils that the core-pieces C³ are brought as near to each other as it is possible to do. Consequently but one or two layers of wire are coiled around said cores. The wires from armature E are brought out through shaft B' to commutator C', and those from armature E' through shaft B to commutator C.

D D' represent brushes for the commutators, designed to be secured in suitable frames or standards. (Not shown in the drawings.)

25 The armatures E E' are designed to be revolved, opposing each other; hence it will be seen from Fig. 2 that the points of opposite polarity of such armatures are always receding from each other while the points of the same polarity are approaching one another. The current forces do not therefore interfere with each other, as the direction of the current in the wire or coil on the inner side of armature E is the same as the direction of the current in the wire or coil on the outer side of armature E', as indicated by the arrows x x, Fig. 1.

I have described armatures constructed to generate tension-currents; but they may also be made of low or decreased resistance or have operating-circuits in parallel without impairing their capacity. Hence I construct the armatures as shown in Figs. 3 and 4, wherein a a', b b', &c., represent the coils or wires thereof wound in sections upon a core in a manner corresponding to the Pachinotti armature, the ends of the sections or helices being located at the points or division-lines between such sections. As shown, there are forty-eight of the sections in each of the armatures, which are provided with sixteen copper rings or sections of rings, H. When the armatures are placed one within the other, as shown in said figures, the rings H for armature E' are located upon its inner side, while those for armature E are placed external thereto, as illustrated. Each ring is connected to its respective armature at two or more points, so as to divide the armature into a series of parallel circuits with appropriate polarity-points, in order to obtain an armature of low resistance.

As the manner of making connection or circuit between the rings H and their armature and commutator is the same for both said armatures, I will only describe such connections for armature E', and in order to more plainly

show the same, the rings H are represented in the form of triangles, Fig. 5, the angles of each triangle representing the points of connection between said rings and armature. Each ring or triangle is connected to the wires coming from the sections a a', &c., or to the armature in three places or points, as shown, and is also in circuit with a commutator-block. Hence each commutator is composed of sixteen blocks, 1 2 3 4, &c.; or there are as many blocks in the commutator as there are rings H on the armature.

In Fig. 5 a brush (not shown) is supposed to be in contact with commutator-block 1, and another brush in contact with block 9, the current entering the former passes from thence, as indicated by arrow y, to connections or sections a a' a² of the armature to make six parallel circuits through the same to sections or connections i i' i² of ring H, connected to the commutator-block 9 and brush in contact therewith. As the armature advances the blocks 8 and 16 are respectively brought in contact with said brushes, whereupon the current enters and leaves the same by means of the next set of rings and their armature-connections, and so on for the entire sixteen rings and commutator-blocks. An armature so constructed has six polarity-points, as indicated by the letters N S in Fig. 5. Such construction gives an armature of one-ninth as much resistance as that of the Pachinotti armature, and theoretically would have but one-third of its capacity; but in practice the capacity of my improved armature is eight or nine tenths of that of a corresponding size Pachinotti and with but one-ninth the resistance, for the reason that in the last-named machine the soft-iron core of the armature must be of a size sufficient to carry the magnetism from the whole coil of the semicircle to the polarity-points, while in my armature the core does not require so large an amount of material, as it has only to carry the magnetism from each shunt or ring connection to the polarity-point for that section. I am therefore able to reduce the amount of metal used in the core of my improved armature, and thereby place the centers of magnetic field nearer together, and so increase the magnetic action or influence in a larger ratio.

I have shown and described armatures having forty-eight sections or helices and sixteen rings H therefor, each making three connections therewith; but it is not to be understood that only the above number may be used, as they may be increased or decreased, as desired, and the rings H may have more than three connections with the armature or less than that number, if desired. The rings H may be segmental sections arranged to form an annulus, or they may be split or mutilated at one or more points, as desired.

The armatures may be arranged adjacent to each other, as shown in Figs. 6 and 7, and are placed upon separate shafts and revolve op-

posing each other; but I do not confine my invention to such arrangement, as the armatures may be located upon parallel shafts, as illustrated in Fig. 8; or three or more armatures may be arranged as shown in Fig. 9. In such case the brushes will be so located as to produce polarity-points, as represented in said figures. In all said described cases, however, it will be noticed that the inducing and induced parts of the armatures move in opposite directions as they pass or are in proximity to each other, and that the core-pieces C thereof are entirely covered or concealed by the endless coils or helices wrapped around them. The advantages of such construction are that the inducing and induced parts of each armature are always in opposing position to each other, such result being obtained irrespective of rates of speed with which the armatures are driven. Hence one armature may be revolved more rapidly than the other, and a continuous current or currents are induced in both armatures, and their full efficiency in working effect is obtained. While, on the other hand, armatures having their cores alternately exposed and concealed must be revolved at equal rates of speed and in unison with each other, so as to bring their inducing and induced parts opposite to each other at the same instant of time; otherwise the inductive action is only partial or is interrupted, thereby producing an intermittent current and a consequent loss of working capacity of the generator.

In all the above-described arrangements of my improved armatures a small permanent or electro-magnetic field is used to initiate the magnetic action in or charge the armatures.

By reversing the location of the brushes and including the armatures in the circuit of an electric battery or generator the device may be used as a motor.

I do not herein broadly claim the combination of two armatures which mutually induce

each other, or which act as a field and an armature for one another; nor do I broadly claim a common circuit, commutator, and brush-connections combined therewith, as they form the subject-matter of a separate and pending application filed July 1, 1882, No. 65,699, of which this is a division.

What I claim as my invention is—

1. In a dynamo-electric machine, the combination of two or more revolving armatures, each of which consists of an iron ring wound with an endless coil of insulated wire, which is, at regular intervals around its circumference, connected to corresponding separate blocks of the commutator therefor, substantially as shown and described.

2. In a dynamo-electric machine, the combination of two or more revolving armatures with their respective commutators, each armature being connected at two or more points around its circumference with each block of its commutator, substantially as shown and described.

3. In a dynamo-electric machine, the combination of two or more iron rings each wound with an endless coil of insulated wire, driving-shafts, and commutators therefor, said coils and commutators being in circuit with each other, substantially as shown and described.

4. In a dynamo-electric machine, the combination of two or more revolving armatures and a series of copper or metal rings for each said armature, each ring having two or more points of connection with its respective armature, and being connected to a block of the commutator therefor, substantially as shown and described.

In testimony whereof I affix my signature in presence of two witnesses.

R. EDWARD BALL.
